PRESSER-FOOT MECHANISM FOR RUG
SEWINGJohn P. Enos, Union, N. J., assignor to The Singer
Manufacturing Company, Elizabeth, N. J., a
corporation of New Jersey

Application April 26, 1949, Serial No. 89,737

14 Claims. (Cl. 112—239)

1

This invention relates to rug sewing machines and more particularly to presser-foot mechanisms used with this type of sewing machine.

The Moran United States Patent No. 1,975,728, issued October 2, 1934, discloses a sewing machine adapted for attaching a binding strip to the raw edge of a rug or carpet. The sewing machine of the Moran patent is equipped with a specially designed plate and a guide member which hold the edge of a rug while the binding strip is being applied.

The present invention has as one of its primary objects the provision of a presser-foot mechanism especially adapted for use in rug sewing.

Another object of the invention is to provide an improved means for stripping the needle of a rug sewing machine and thereby effectively preventing flagging of the work and skipping of stitches.

A still further object of the invention is the provision of an improved presser-foot that will have both up-and-down movement with respect to a rug being sewed, as well as to-and-fro movement transversely of the line of stitches being formed.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a front elevational view of a portion of a rug sewing machine equipped with a presser-foot mechanism embodying the present invention.

Fig. 2 is a fragmentary plan view taken substantially on the broken line 2—2 of Fig. 1.

Fig. 3 is a fragmentary view, partly in front side elevation and partly in section, showing the presser-foot mechanism in the act of pressing a rug against a guide.

Fig. 4 is a fragmentary view similar to Fig. 3 but showing a modified form of the invention, and

Fig. 5 is a plan view of some of the parts shown in Fig. 4.

A sewing machine 10, portions of which are illustrated in the accompanying drawings, is of known construction and is provided with the usual bed-plate 11, and the overhanging bracket-arm 12 terminating in a head 13 having a face

2

plate 14 and housing the usual mechanism for operating a needle 15. A main shaft 16 is journalled in the arm 12 and carries an eccentric 17 for imparting reciprocating motion to a pitman 18 which, at its lower end, is connected to a mechanism 19 for operating a top-feeding wheel 21. The sewing machine and the feeding mechanism are fully disclosed in the Moran Patent No. 1,975,728 and, therefore, require no further description.

The presser-foot mechanism under consideration comprises an L-shaped operating lever 26, the major portion of which is positioned in a vertical plane. The L-shaped lever 26 is provided with a substantially vertically disposed leg 27 having an offset 25. The lower end of the leg 27 is fulcrumed on a pivot pin 28 that extends parallel to the line of feed and the pivot pin is carried by an upstanding flange of an angle bracket 29, the base of the angle bracket being held to a plate 31 by screws 32—32. The plate 31 is adjustably secured to the sewing machine bed-plate 11 by screws 33—33 passing through slotted holes 34—34 provided in the plate 31. The other arm 36 of the L-shaped lever 26 is disposed substantially horizontally and extends from the upper end of the vertical leg 27 in a direction away from the needle 15 of the sewing machine.

The L-shaped lever 26 is rocked toward and away from the needle 15 by a lost motion connection comprising one horizontally extending arm 37 of an L-shaped pin 38 that enters a slotted aperture 39 provided in the arm 36. The other arm 41 of the L-shaped pin 38 is horizontal and formed integral with a notched block 42, which by means of a second notched block 43 and screws 44—44, is clamped to the pitman 18.

A presser-foot 48, having a sole-plate 49 apertured by an oblong needle-hole 51 extending normal to the line of stitches, is provided with an arm 52, extending from one side of the sole-plate. The arm 52 is upwardly curved as at 53 and is twisted ninety degrees (90°) as at 54. An upper end 56 of the arm 52 is provided with a hole 57 by which a headed pin 58 pivotally holds the end 56 to the arm 27 of the operating lever 26.

A stiff wire spring 61 causes the sole-plate 49 of the presser-foot 48 to be biased downwardly about the pin 58. The upper terminal of the spring 61 is held to the upper end of the leg 27 by a screw 62 and by virtue of having the end 63 of the spring 61 hooked about the arm 27. The other end 64 of the spring 61 is curved and slidably engages the upper face of the presser-foot sole-plate 49.

The curved and twisted arm 53—54 of the

3

presser-foot 48 has a shoulder 66 (Fig. 1) that engages a front forward edge 67 of the vertical leg 27 of the operating lever 26. This shoulder 66 limits the lowermost position to which the spring 61 can move the sole-plate 49. The shoulder 66 also provides a means for lifting the presser-foot 48 when the operating lever 26 is rocked in a direction away from the needle 15. The front edge of the sole-plate 49 is rolled upwardly as at 68 and thus provides easy ingress for the rug being 10 sewed.

As previously stated, the Moran Patent No. 1,975,728 fully illustrates and discusses the sewing machine used to attach a binding-strip to the raw edge of a rug. Because of this, a detailed description of the sewing machine is not deemed necessary. Suffice it to say: The feed-wheel 21 presses yieldingly upon the back face of a rug R (Fig. 3) as it is passed, pile face down, over a thick work-supporting plate 71 slotted at 72 to receive fastening screws 73. The plate 71 is beveled at 74 and thereby provides a work-guiding edge against which the pile of the rug is pressed. The plate 71 has an upstanding rib 76, curved at its front end as at 77. A pair of screws 78-79 pass through the rib 76 thereby supporting a rug-edge-bending guide 79. Since the plate 71 is adjustable, the guide 79 is also adjustable transversely of the line of seam formation, thereby making it possible to cause the needle 15 to penetrate the bent edge E of the rug R at the desired distance from the edge of each alternate thrust.

The guide 79 has an upstanding guide wall 81 which cooperates with the beveled end 74 of the plate 71 to define a passageway. The guide 79 and the plate 71 guide the rug R during the sewing operation. The guide 79 also has an overhanging arm 82 toward the front and a second overhanging arm 83 toward the rear thereof. The under surfaces of these arms are curved and thereby further assist in guiding the rug R.

Reference to Fig. 2 indicates that the guide 79 has been cut away between the portions indicated by the numerals 84 and 86. This provides space 45 for the presser-foot 48 to descend a sufficient distance to engage the rug R when the presser-foot is in its lowermost position.

It will be appreciated that, as the main shaft 18 rotates during the normal operation of the sewing machine, the eccentric 17 will impart reciprocating motion to the pitman 18, the blocks 42-43 and the L-shaped pin 38. The up-and-down movement of the arm 37 of the pin 38 causes the operating lever 26 to rock about the pivot pin 28.

The rocking movement of the operating lever 26 imparts two motions to the presser-foot 48, one an up-and-down motion and the other a horizontal to-and-fro motion. Normally, the presser-foot 48 is pressed downwardly by the spring 61. However, when the lever 26 has moved in a direction far enough away from the needle 15, the shoulder 66 of the arm 52 engages the edge 67 of the vertical leg 27. Further rocking movement of the arm 26 away from the needle 15 causes the presser-foot 48 to be raised substantially vertically away from the rug R.

The to-and-fro movement of the presser-foot is at right angles to the needle 15 as well as at right angles to the line of stitches. As the lever 26 is rocked toward the needle 15, the sole-plate 49 of the presser-foot 48 moves downwardly and engages the back face of the rug R. As the downward movement of the sole-plate 49 is

4

stopped by the rug R, the arm 52 pivots on the pin 53 against the pressure of the spring 61. This causes the sole-plate to move to the left from the position shown in solid lines in Fig. 3 to the position shown in dotted lines. Preferably, the mechanism will be timed so that the needle 15 and the presser-foot 48 move downwardly together. Thereafter the needle 15 starts to rise while the presser-foot 48 continues to descend. Eventually, the presser-foot 48 will begin to rise.

From the above it will be seen that the downward movement of the presser-foot 48 presses the rug R against the plate 71, holding it there until after the needle 15 has started to rise. This of course strips the needle and prevents flagging of the rug R which if present might cause skipping of stitches. Also the movement of the presser-foot 48 in a direction toward the beveled edge 74 (see Fig. 3) tends to crowd the rug R against the beveled edge 74 and thus positions the rug for proper engagement by the needle 15.

Figs. 4 and 5 illustrate a modified form of the invention. The construction shown in Figs. 4 and 5 is identical with the construction previously described except that the sole-plate 49' of the presser-foot 48' is apertured with a square hole 88 which accommodates one depending arm 89 of an angle shaped pusher or compressor 91. The other substantially horizontal arm 92 of the compressor 91 is provided with a pair of slotted holes 93-93. A screw 94 passes through each of these holes and by virtue of being screwed into threaded holes in the sole-plate 49' adjustably secures the pusher 91 to the presser-foot 48'. The arm 89 makes an angle of slightly more than ninety degrees (90°) with the arm 92 and when the pusher 91 is installed the arm 89 passes through the hole 88 and depends below the bottom of the sole-plate 49'. This, as best seen in Fig. 4, places the pusher arm 89 in position to engage the back face of the rug R and it will be understood that when the presser-foot 48' executes its to-and-fro movement that the pusher arm 89 will crowd the rug R into intimate engagement with the beveled edge 74 of the plate 71. This assures proper and accurate positioning of the rug R with respect to the plate 71 and the needle 15.

Having thus set forth the nature of my invention, what I claim herein is:

1. A sewing machine presser-foot mechanism comprising an L-shaped lever, means for pivotally mounting one end of said L-shaped lever, a presser-foot pivotally supported from said L-shaped lever, and means for rocking said L-shaped lever about said pivotal mounting, whereby said presser-foot is caused to have a to-and-fro movement.

2. A sewing machine presser-foot mechanism comprising an L-shaped lever, means for pivotally mounting one end of said L-shaped lever, a pin carried by said L-shaped lever, a presser-foot pivotally supported from said pin, and vertically reciprocating means for engaging said L-shaped lever and thereby rocking said lever about said pivotal mounting, whereby said presser-foot is caused to have a to-and-fro movement.

3. A sewing machine presser-foot mechanism comprising a lever having a pivotally mounted lower end, means for causing to-and-fro pivotal movement of said lever, a presser-foot arm pivotally mounted on said lever, a sole-plate supported by the free end of said presser-foot arm, a shoulder formed on said arm and arranged to engage said lever, whereby when said lever is

rocked in one direction said arm and presser-foot will be raised by the movement of said lever, and a spring arranged to bias said arm and sole-plate downwardly to cause engagement of said shoulder with said lever.

4. A sewing machine presser-foot mechanism comprising a lever having a pivotally mounted lower end and a front edge, means for causing to-and-fro rocking movement of said lever, a presser-foot arm pivotally mounted on said lever, a sole-plate supported by the free end of said presser-foot arm, a 90° bend in said arm, a shoulder formed by said 90° bend and arranged to engage said front edge of said lever, whereby, when said lever is rocked in one direction, said arm and presser-foot will be raised by the movement of said lever, and a spring carried by said lever and arranged to bias said arm and sole-plate downwardly to cause engagement by said shoulder with said front edge.

5. In a sewing machine having a bed-plate, an overhanging bracket arm, a main shaft journaled in said bracket arm, and a reciprocating needle supported from said bracket arm and actuated by said shaft, a roller feed wheel, and a reciprocating pitman for operating said feed wheel from said main shaft; a presser-foot mechanism, comprising, an L-shaped lever having a pair of arms, means for pivotally supporting a first of said arms from said bed-plate, a lost motion pin connection between a second of said arms and said reciprocating pitman, a presser-foot pivotally mounted on said first arm and having a needle hole for accommodating said needle, and a spring supported from said L-shaped lever and arranged to bias said presser-foot toward said bed-plate.

6. In a sewing machine having a bed-plate, an overhanging bracket arm, a main shaft journaled in said bracket arm, and a reciprocating needle supported from said bracket arm and actuated by said shaft, a roller feed wheel, and a reciprocating pitman for operating said feed wheel from said main shaft; a presser-foot mechanism, comprising, an L-shaped lever having a pair of arms, means for pivotally supporting the lower end of a first of said arms from said bed-plate, the second of said arms being provided with a horizontally extending slotted aperture, an L-shaped horizontally positioned pin carried by said reciprocating pitman and engaging said slotted aperture, a presser-foot having a bent and twisted arm, means for pivotally mounting said twisted arm on said first arm of said L-shaped lever, said presser-foot having a needle hole for accommodating said needle, and a spring supported from said L-shaped lever and arranged to bias said presser-foot toward said bed-plate.

7. In a sewing machine having a bed-plate, an overhanging bracket arm, a main shaft journaled in said bracket arm, a reciprocating needle supported from said bracket arm and actuated by said shaft, a roller feed wheel, and a reciprocating pitman for operating said feed wheel from said main shaft; a presser-foot mechanism, comprising, a lever positioned in a vertical plane that is parallel to said main shaft, means for pivotally supporting said lever, means for rocking said lever toward and away from said needle, a presser-foot pivotally supported from said lever and having a needle hole for accommodating said needle, and a spring engaging said presser-foot and thereby biasing said presser-foot toward said bed-plate.

8. A sewing machine presser-foot comprising a lever, means for pivotally mounting one end of

said lever, a presser-foot pivotally supported from said lever, means for rocking said lever about said pivotal mounting, whereby said presser-foot is caused to have a to-and-fro movement, and a pusher member secured to and depending below said presser-foot.

9. A sewing machine presser-foot mechanism comprising an L-shaped lever, means for pivotally mounting one end of said L-shaped lever, a presser-foot arm pivotally supported from said L-shaped lever, a sole-plate carried by the free end of said presser-foot arm, a pusher member depending below said sole-plate, and means for rocking said L-shaped lever about said pivotal mounting, whereby said pusher member is caused to have a to-and-fro movement.

10. In a sewing machine having a bed-plate, a work support guide plate carried by said bed-plate, an overhanging bracket arm, a main shaft journaled in said bracket arm, a reciprocating needle supported from said bracket arm and actuated by said shaft, a roller feed wheel, and a reciprocating pitman for operating said feed wheel from said main shaft; a presser-foot mechanism, comprising, an L-shaped lever having a pair of arms, means for pivotally supporting a first of said arms from said bed-plate, the second of said arms being provided with an aperture, means carried by said reciprocating pitman and engaging said aperture and thereby rocking said lever, a presser-foot sole-plate, an arm secured to said sole-plate, means for pivotally mounting said presser-foot arm on said first arm, a pusher member depending below said sole-plate, and a spring supported from said L-shaped lever and arranged to bias said presser-foot and pusher arm toward said bed-plate, whereby when said pitman is reciprocated, said pusher member is caused to have a to-and-fro movement.

11. In a sewing machine having a bed-plate and a reciprocating needle, a work-supporting plate provided with a work-guiding edge, a complementary work-guide spaced from said guiding edge and providing a passageway therebetween for a downwardly bent margin of work passing over said work-supporting plate, a movable presser member overhanging said passageway, a hinge member for pivotally mounting said movable presser member, and means operating in timed relation with the reciprocations of said needle to move said presser-member into and out of engagement with the work.

12. In a sewing machine having a bed-plate and a reciprocating needle, a work-supporting plate provided with a work-guiding edge, a complementary work-guide spaced from said guiding edge and providing a passageway therebetween for a downwardly bent margin of work passing over said work-supporting plate, a movable presser member overhanging said passageway, a member for movably supporting said movable presser member, and means operating in timed relation with the reciprocations of said needle to actuate said presser-member in transverse directions to engage and disengage the work and to crowd the work-margin toward said work-guiding edge.

13. In a sewing machine having a bed-plate and a reciprocating needle, a work-supporting plate provided with a work-guiding edge, a complementary work-guide spaced from said guiding edge and providing a passageway therebetween for a downwardly bent margin of work passing over said work-supporting plate, a movable presser-member overhanging said passageway,

a compressor arm carried by and depending below said presser-member, and means operating in timed relation with the reciprocations of said needle to move said presser-member into and out of engagement with said work.

14. In a sewing machine having a bed-plate and a reciprocating needle, a work-supporting plate provided with a work-guiding edge, a complementary work-guide spaced from said guiding edge and providing a passageway therebetween for a downwardly bent margin of work passing over said work-supporting plate, a movable presser-member overhanging said passageway, a member for movably supporting said movable presser member, a compressor arm carried by and depending below said presser-member and enter-

ing said passageway, and means operating in timed relation with the reciprocations of said needle to actuate said presser-member and compressor arm in transverse directions to engage and disengage the work and thereby crowd the work toward said work-guiding edge.
